UNITED STATES PATENT OFFICE.

WILLIAM W. WALTERS, OF SALEM, MISSOURI.

AUTOMATIC CORN-DROPPING ATTACHMENT.

SPECIFICATION forming part of Letters Patent No. 374,815, dated December 13, 1887.

Application filed June 14, 1887. Serial No. 241,273. (No model.)

To all whom it may concern:

Be it known that I, WILLIAM W. WALTERS, of Salem, in the county of Dent and State of Missouri, have invented a certain new and useful Improvement in Automatic Corn-Dropping Attachments, of which the following is a full, clear, and exact description, reference being had to the accompanying drawings, forming part of this specification, and in which—
10 Figure I is a side elevation showing the pitman-rods in their operative positions. Fig. II is a top plan view showing the pitman-rods in intermediate positions. Fig. III is a vertical longitudinal section taken on line III III, 15 Fig. II, showing the pitman-rods relatively in their two intermediate positions attached to a depressed and elevated crank and seated in the swivel-heads of the pivoted operating T-lever, in which they have their slide-bearings; 20 and Fig. IV is a section taken on line IV IV, Fig. II, showing the swivel-head of the T-lever, with its set-screw that secures its attachment and the peripheral channel-groove in which it works.

25 This invention relates to devices for automatically operating the seed-slides of corn-planters; and the invention consists in features of novelty, hereinafter fully described, and pointed out in the claims.

30 This invention is adapted for attachment to corn-planters in general, and especially to the check-row attachments patented to Andrew J. Walters June 14, 1887, No. 364,981.

I will describe my invention as attached to 35 a corn-planter, not claiming any features outside the devices for operating the seed-slide that controls the dropping of the corn, including the double-crank axle, pitman-rods, swivel-headed pivoted T-lever operating the seed-slide, &c.

Referring to the drawings, in which similar figures of reference indicate like parts in all the views, 1 represents the longitudinal beams, 45 and 2 the transverse beams, of the rectangular transporting-frame of a corn-planter to which my invention is attached. The frame is provided with box-bearings 3 near the middle of its length, that carry the axle 4, upon the spin-

50 dles 5 of which run the transporting or covering wheels 6.

Running transverse to the transporting-frame

is the check-rower and corn-dropper frame 7, which is rigidly secured to the former frame, the front end of the transporting-frame being 55 attached to the rear transverse beam, 8, of the dropper-frame, which beam is jointed to the short side beams, 9, of said frame, the said beams carrying the front transverse beam, 10, which is secured to them by bolts 11 from beneath. The relative positions vertically of the transverse beams 8 and 10 give the proper 60 slightly-vertical inclination to the tongue 12, which is lap-jointed to the former and rests on and is secured to the latter. The dropper-frame 7 is supported on runners 13, which are connected directly to the frame in front, at 51, and to the pendent metallic seed spout or conductor 14 at the rear. A double-crank shaft, 15, works in three pendent box-bearings, 16, 70 that are bolted or otherwise secured relatively beneath the side beams, 9, and the tongue 12.

The crank-shaft 15 carries the rimless drive-wheels 17, broad spokes or paddles 18 of which have their interradiate ends secured in socket-holes 19 of the center wheels, 20, the spokes 21 of which connect with the hubs on the ends of said crank-shaft. The outer ends of the spokes of the rimless drive-wheels are of a 75 shape to enter the ground freely, which they 80 do to about the same depth as the runners.

Projecting from the hubs are arms 22, to which are pivoted two pairs of marker or indicator arms, 23—one pair to each wheel. The end portions of each pair of arms are connected together loosely by links 24 and a rod, 25. The arms are pressed away from each other by means of bow or curved springs 26, whose bifurcated ends 27 engage notched portions 28 of the arms. Sliding balls or weights 29 play on the rods 25, and by their gravity 90 throw the marker-arms into perpendicular at the time of marking.

The marker-point marks half-way between the last row planted and the next row to be 95 planted.

I now proceed to describe the actuating devices for effecting the drop in connection with the double-crank shaft or axle already mentioned, which, together with said crank-axle, 100 are the novel features pointed out in and covered by the claims appended to and forming part of this specification.

30 represents pitman-rods that have split

flanged shoulders 31 and curved arms or clips 32, that embrace the bearings 33 of the cranks 34 on the shaft 15. Screw-nutted bolts 35 secure the clips around the bearings that they 5 embrace. The forward ends of the pitman- rods have slide-bearings 36 in the swivel-heads 37, that are secured by set-screws 38, whose points work in the peripheral channel-grooves 39 as the swivel-heads turn on the cross-arms 10 of the pivoted T-lever 40. The pitman- rods are double-locked in their slide-bearings in the swivel by nuts 41, that engage on the threaded ends of the pitman- rods.

The head of the T-lever has pivotal bearing 15 on the bolt 42, that is secured in the tongue near the line at which it crosses the beam 10. The circular foot 43 of the swivel-headed T-lever works in the channel-grooves within the forks 44 of the bifurcated lever 45, which 20 lever is pivoted on the bolt 46, that is seated in the tongue, providing a short arm at the forward end of the lever and a long one at the rear end, where, within an elongated slot, 47, an anti-friction roller, 48, slides. Said roller 25 is secured on a pin, 49, that projects from the seed-slide 50. The seed-slide has perforations or valves 52, (shown in dotted lines in Fig. II,) which, as relatively they are brought into coincidence with the discharge-valves of the 30 hoppers, discharge their measures of seed.

In the operation of the device it will be seen that twice in each revolution of the rimless drive-wheels the double-crank shaft operated by them actuates the pitman-rods (in alternate action) when their nut-heads strike the swivel-heads of the pivoted T-lever and relatively throw its foot round to the right or left, thereby actuating the pivoted bifurcated lever 45 to enforce the longitudinal movement 35 of the seed-slide to open the discharge-valves in the hopper and deliver the measured quota of seed. When the pitman-rods are in their intermediate positions, as shown in Figs. II and III, the valves in the seed-slide not being in line coincident with the discharge-valve beneath the center of the hopper, seed cannot be discharged or leak from the hopper; but when in the position shown in Fig. I, in which one of the pitman-heads has just operated on 45 the swivel-head of the T-lever, which it has thrown round, the seed-slide thereby being longitudinally thrown, the valve of necessity 50 must deliver its quota of seed.

I do not confine myself to any form of discharge-valve for the hopper. Any suitable valve or discharge adapted for alternating operation with seed-slides may be used.

It will be seen that a great advantage is gained by applying the power in front of 55 main shaft and utilizing the tongue and the forward frame beneath it to carry my pitman- swivel devices for the automatic operation of the seed-slide.

I claim as my invention—

1. In attachments for corn - planters, the 65 combination of the double-crank axle 15, that operates the pitman-rods 30, the pivoted T-lever 40, with swivel - heads 37 on its cross-arms, in slide bearings of which said pitman- rods work, and the screw-nuts that engage on the 70 forward ends of said rods, and arranged when they alternately strike the swivel-heads of the cross-arms to throw round the foot 43 of the T-lever and force round the forks of the pivoted lever 45, thus forcing its rear arm in an 75 opposite direction and causing the longitudinal movement of the seed-slide 50, with which it connects, so as alternately to open and close the seed-valves 52 in the hopper and drop the corn in check-rows, substantially as described, 80 and for the purpose set forth.

2. In attachments for corn - planters, the combination of the pitman-rods secured by clips 32 to bearings 33 of the cranks 34 of the axle 15, said rods having slide-bearings in the 85 swivel-heads of the T-lever 40, pivoted to the tongue, and arranged as the adjustable nut-heads 41 on the rods strike the swivel-head to carry round the foot of said T - lever and operate the pivoted lever 45, in the elongated 90 slot 47 of which works an anti-friction roller on the pin 49, that projects from the seed-slide, and thus works the slide longitudinally to alternately open and close the valve through 95 which the corn is dropped, substantially as and for the purpose set forth.

3. In attachments to corn - planters, the combination of the double - crank axle, the cranks of which operate the pitman-rods that work in slide-bearings in the swivel-headed T-lever, and by the foot of said lever actuate the pivoted lever 45, which connects with the seed-slide by an anti-friction roller, and pin working in an elongated slot in the lever, so as to move 100 said slide longitudinally and alternately open and close the seed-valves twice in each revolution of the shaft 15, thus arranged to drop the corn in its check-row, substantially as described, and for the purpose set forth.

4. In attachments for corn - planters, the combination of the double-crank axle, pitman- rods sliding in bearings in the swivel-headed T-lever, which operates the bifurcated pivoted lever 45, that connects with the seed-slide to move said slide longitudinally twice during 115 each revolution of the drive-wheels, and said double-crank shaft to alternately open and close the valves of the hopper and drop the corn at regular intervals, the power being applied in front of the main axle, substantially 120 as and for the purpose set forth.

WILLIAM W. WALTERS.

In presence of—

BENJN. A. KNIGHT,
JOS. WAHLE.
